United States Patent Office.

J. G. FOSTER, OF NASHUA, NEW HAMPSHIRE.

Letters Patent No. 92,597, dated July 13, 1869.

IMPROVED COUNTERPOISE GUN-CARRIAGE.

The Schedule referred to in these Letters Patent and making part of the same.

To all whom it may concern:

Be it known that I, J. G. FOSTER, of Nashua, in the county of Hillsborough, and State of New Hampshire, have invented certain new and useful Improvements in Counterpoise Gun-Carriages; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to counterpoise gun-carriages; and

The invention consists in so constructing and arranging the carriages that they shall turn on a centre pintle, which pintle, with the gun and its carriage, shall be depressed by the recoil of the gun when discharged, the gun moving in the arc of a circle, and being so counterbalanced by weights below that it shall automatically rise into position for being fired, as herein-after more fully explained.

In the drawings—

Figure 1 is a perspective view;

Figure 2, a side elevation;

Figure 3, a top plan view; and

Figures 4 and 5, elevations of the weights and fixtures below.

The apparatus consists of a circular track, R, secured firmly in place, and having mounted thereon a traverse-carriage, A, made in any suitable manner, but having its cheeks so made that their upper edges shall form an arc of a circle, as represented in figs. 1 and 2, the arc being described from the centres of the ends of a cross-rod, l, located near the bottom, and about one-third of the length of the carriage from the front end thereof, this traverse-carriage being provided with wheels, to run on the track, and being secured to the track, also, by strong clamps, T, at front and rear, which clamps engage under a projecting flange made on the track for that purpose, as shown in figs. 1 and 2.

To this traverse-carriage, the gun-carriage C, which may be of the ordinary construction, is connected by two parallel arms or rods, I, on each side, these arms being pivoted, at their upper ends, on two axles, N, passing transversely through the lower part of the gun-carriage C, while their lower ends are similarly pivoted on two rods, l and l', passing transversely through the lower part of the traverse-carriage A, the parallel arms I being shown by dotted lines in fig. 2, and partially shown in perspective in fig. 1.

A chassis, B, is placed within the traverse-carriage, between the arms I, and under the gun-carriage C, as represented in figs. 1 and 2, this chassis consisting of two strong rails, made deepest at their centre, and tapering gradually toward each end.

This chassis is pivoted and supported, at its centre, upon a strong vertical shaft, D, which passes through a pintle-block, J, at the centre of the track R, and extends down into a casemate below, if on a fort, or into a well provided for the purpose, if in earthworks.

At its lower end, this shaft D rests and turns in a step or bearing, V, which latter works freely between vertical guides U, as represented in figs. 4 and 5.

This step V is connected, by strong cords m, which pass up over pulleys H, mounted in suitable bearings above it, to weights W, as represented in fig. 4, these weights being sufficiently heavy to counterbalance the gun and its carriage, with the chassis and its shaft D.

It will thus be seen that the gun and its carriage, instead of resting on and being supported by the traverse-carriage, rest upon the chassis B, and, with the chassis, are supported by the counterpoise-shaft D, which, in turn, is supported by the weights W.

The chassis is so connected to the shaft D as to incline forward just enough to permit the gun to run easily into battery, or position for firing.

Upon the axles N, of the gun-carriage C, are placed flanged wheels h, which rest and traverse on the chassis; and the rear axle N protrudes, at each side, through and beyond the cheeks of the carriage C, and has secured on its outer ends another pair of flanged wheels, G, which rest lightly on the curved edges of the traverse-carriage A, as shown in figs. 1 and 2.

If desired, the front axle N may have its ends also protrude beyond the cheeks of the gun-carriage, and work in curved grooves, formed by curved ribs or bars, secured to the inner sides of the cheeks of the traverse-carriage, the curved bars or ribs being indicated by P in figs. 1 and 2, though this latter arrangement I do not consider absolutely necessary.

The arms I, where they are connected to the axles N of the gun-carriage, are slotted, so as to allow of a little play of the axles; and the rods l and l', to which their lower ends are connected, are mounted in sliding boxes, which are held down by a strong rubber spring, n, as shown in fig. 2, the object being to assist in preventing or absorbing any shock caused by the gun as it runs into battery. For the same purpose, rubber springs or buffers, a, are secured to the traverse-carriage A, as shown in fig. 2, there being also similar buffers, b, at the rear, to check the gun, and prevent a sudden shock, as it is thrown back by the recoil.

A heavy rubber cushion, E, is also placed around the shaft D, directly under the chassis, which cushion also assists to absorb the shock when the gun is forced down by the recoil, the cushion being compressed between the cross-bar or plate of the chassis and of the traverse-carriage below.

To the rear end of the chassis is secured a strong vertical bar, F, having ratchet-teeth on it, as represented in figs. 1 and 2; and to the traverse-carriage is

pivoted a spring-pawl, *o*, which engages with the teeth of the ratchet as the chassis is depressed, and holds it down until released.

The pawl *o* is connected to and operated by a lever, *L*, which also has an arm, *r*, extending downward, and connecting with a sliding rod, *O*, which works in suitable bearings, and has, at its front end, a brake-block, which bears against the counterpoise-shaft *D*, and thus serves to regulate the motion of the shaft as it rises, and, consequently, the motion of the gun as it runs into battery.

Instead of a shore bearing against the shaft, a band passing around it may be used for a brake; and it may be connected with the lever that operates the pawl, or with a separate one, as may be preferred.

As a further means of controlling and regulating the movements of the gun, I also make the counterbalance of a series of weights, so connected and arranged, that as the gun recoils, the weights, instead of all being moved at once, will be taken up successively, one after another, as the gun recedes, the series of weights being connected by slotted bars *e*, as shown in fig. 4, or by any equivalent means. I also propose to construct the arms *I* with counterpoise-weights, *u*, at their lower ends, as represented in fig. 2, so that they will be balanced on the rods *l* and *l'*, whatever position they may assume.

In mounting the apparatus on a fort, the counterpoise will be placed in a casemate underneath, and may be so arranged as to leave room in front of the guides *U* and shaft, to permit a casemate-gun to be operated there.

It is obvious, that instead of having the weights arranged or located as represented, they may be placed at any desired point by simply carrying the cords *m* off to the desired position, and passing them over pulleys suitably located.

It is also obvious, that by a suitable system of gearing, the weights may be increased, and made to move through a correspondingly less space; or their weight may be decreased, and their travel increased, to suit the circumstances of the location or place.

With the parts thus constructed, the operation is as follows:

The gun, being loaded, and in position, is fired; and, when fired, the recoil drives it backward on the chassis; but, being held by the arms *I*, as it moves back,

it is drawn down, forcing the chassis and shaft down with it, the gun, with its carriage, moving in the arc of a circle, with its wheels *G* on the circular or curved portion of the traverse-carriage, until they strike the buffers *b*, its descent being regulated by the brake, if desired or necessary. As the gun is thus lowered by its recoil, it is in sheltered position behind the parapet or breastwork, where it can be reloaded in safety; and, when loaded again, it is only necessary to release the pawl *o*, when the gun rises, and moves forward into battery, ready to be fired again. It can be turned or traversed, as desired, either when up or down, as may be necessary.

By these means, I construct a very simple, compact, and complete apparatus for working guns of any size.

Having thus described my invention,

What I claim, is—

1. The combination of the traverse-carriage *A* and the gun-carriage *C*, the two being connected by the parallel arms *I*, by which the gun is made to move in the arc of a circle, substantially as and for the purpose set forth.

2. The counterpoise-shaft *D*, arranged to support the chassis *B*, and passing through the centre of motion of the traversing-carriage *A*, whereby the gun can be freely traversed in any direction, whether in or out of battery, substantially as described.

3. The combination of the chassis *B*, traverse-carriage *A*, and gun-carriage *C*, with the parallel arms *I*, when arranged to operate substantially as herein described.

4. The combination of the chassis *B*, rotating shaft *D*, mounted in a sliding step, *V*, and the counterbalance or weights *W*, when constructed and arranged to operate substantially as described.

5. So arranging the counterbalance-weights that they shall come into operation, and be taken up, successively, substantially as and for the purpose herein described.

6. The application of the brake *O*, or its equivalent, to the counterpoise-shaft *D*, for the purpose of regulating the movement of the gun, as set forth.

J. G. FOSTER.
